Primary Examiner — Aula Soroush*(74) Attorney, Agent, or Firm* — Bayramoglu Law Offices LLC(57) **CLAIM**

The ornamental design for a pet car seat cover, as shown and described.

DESCRIPTION

FIG. 1 is a perspective view of a pet car seat cover showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof the right side being mirror image;

FIG. 7 is an alternate configuration of the top plan inner view thereof; and,

FIG. 8 is an alternate configuration of the bottom plan view thereof.

The broken lines showing portions of the pet car seat cover form no part of the claimed design.
